BATHING ACCESSORY

Harry Shoglow, Cambridge, Mass., assignor to
Patent Products Corp., Boston, Mass., a cor-
poration of Massachusetts

Application September 14, 1936, Serial No. 100,737

9 Claims. (Cl. 135—1)

The present invention relates to improvements in bathing beach accessories to enable bathers to change their clothes quickly and conveniently at the bathing site. Devices which have been used for the purpose comprise beach tents and shelters of various kinds which in general involve some fairly rigid skeletal feature for maintaining the device in position for use; the presence of the rigid element affecting the portability of the accessory to a lesser or greater degree.

A primary object of this invention is to provide a bathing accessory which is light in weight, entirely flexible and extremely portable.

Another object of this invention is to provide a bathing accessory which is inexpensive, simple to manufacture and comfortable to use.

Still another object of this invention is to provide a bathing accessory which may be readily converted into a bag for storing and transporting articles.

A further object of this invention is to provide a bathing accessory which because of its complete flexibility permits itself to be used for a variety of purposes on the beach.

Other objects and advantages of the device will be apparent from a consideration of the description presented below and the accompanying drawings, in which drawings;

Fig. 1 is a perspective view of a bathing accessory embodying the invention,

Fig. 2 is an enlarged view of the side opening shown in Fig. 1,

Fig. 3 is a front view of the accessory folded to serve as a carrying bag,

Fig. 4 is a bottom view of a bathing accessory having a bottom section set in to join the sides,

Fig. 5 is a side view of a modification of the bathing accessory shown in Fig. 1,

Fig. 6 is a view along the line 6—6 of Fig. 5,

Fig. 7 is an edge view of the fabric arranged for making the bathing accessory of Fig. 5,

Fig. 8 is a perspective view of a hood adaptable for use with the bathing accessories of Figs. 1 and 5,

Fig. 9 is a fragmentary view of a modification.

Referring to the drawings, the numeral 1 designates generally the body of a tubular structure preferably closed at the bottom 2, and provided with an opening 3 at the top and preferably two side openings 4 and 5 located near the top. The top edge 6 of the tube is hemmed and shirred onto a circular elastic band 7 which normally maintains the opening 3 in an almost completely closed condition. If desired a drawstring or other

suitable means may be substituted for the elastic band.

The side openings 4 and 5 are preferably kept contracted by means of circular, preferably elastic bands 8 and 9 enclosed by the hems 10 and 11. In addition, flaps 12 and 13 may be attached to the front 14 of the tube and above and below the side openings. This latter feature assists in preventing a view of the interior of the accessory through the side openings when it is in use.

If it should be desired to use the bathing accessory as a bag for carrying articles, handles 15 and 16 made of fabric similar to that used in making the accessory may be stitched to corresponding points on the front 14 and the back 17. The handles should be located sufficiently near the bottom to enable carrying the formed bag, Fig. 3, conveniently.

In making the bathing accessory shown in Fig. 1 it is first merely necessary to double a length of fabric with the bend at the bottom. If desired, two separate side pieces may be utilized and the bottom left open or a separate piece 18 of any shape desired may be stitched to the bottom edges as shown in Fig. 4. If the bottom is left open it may, if desired, have an elastic band or other suitable element 37 for contracting the opening inserted in a hem at the edge. The accessory is completed by stitching the side edges together while providing for the side openings, inserting the elastic bands 1, 8, and 9 and attaching the flaps 12 and 13 and the handles 15 and 16.

The modified accessory shown in Fig. 5 is made by doubling the fabric 19, Fig. 7, so that the back 20 is longer than the front 21. The side edges are then stitched from the bottom up to the lower corner 22 of the side opening where the edges are firmly attached by several rows of stitching 23. The edge of the back 19 from 22 to 24 is hemmed and shirred onto an elastic strip 25 the ends of which are firmly attached to the fabric at 22 and 24. The gathering of the fabric on the elastic strip 25 tends to bring the top edge 26 of the back 20 in line with the top edge 27 of the front portion 21. The side edges of the back 20 from the point 22 upward are now lapped over the side edges of the front 21 in the manner shown in Fig. 5 and stitched along the lines 28, 29, and 30. The result is a side opening which is completely covered and which may be distended to a considerable size. A circular elastic band 31 may now be inserted in a hem 32 at the top, as in the previously discussed embodiment of the invention. In making the accessory as described above an enlargement 33 is created in the upper

part of the back which is of advantage in that the fullness of the back permits the bather to bend over when reaching for articles of wear on the beach without restraint.

5 In the modification presented here the means for adapting the beach accessory for use as a carrying bag consists of a drawstring 34 passing through several loops 35 stitched laterally around the accessory, as shown in Fig. 5. The carrying 10 bag is formed by pushing the upper part of the accessory inwardly and downwardly on a line with the drawstring 34. Pulling the ends of the drawstring taut will completely close the opening of the formed bag.

15 In using the bathing accessory, the elastic band 7 is first expanded to its fullest extent to permit the bather to step into it and pull it up until the edge 6 is on a level with the neck when the elastic band 7 is allowed to close as much 20 as possible about the neck of the bather. Now, by thrusting the arms through the side openings 4 and 5 the bather can reach out for various articles previously conveniently located and then, reinserting the arms, make the desired change 25 of clothing. When dealing with an article which is put on by slipping over the head and shoulders, the edge 6 is merely slipped over the head of the bather, thus permitting the article to be put on in the customary manner. Or, if desired 30 the edge 6 may be slipped under the armpits, the garment placed over the head and the arms slipped through the sleeves when the edge 6 can be returned to its original position around the neck. The accessory should, of course, be suffi- 35 ciently long to extend above and fully enclose the head of the bather when necessary. It should also have sufficient width so that the desired changes of clothing can be made in comfort. It will be apparent that the bathing ac- 40 cessory described here affords as great a degree of privacy as is obtainable with any of the more complicated devices now extant for accomplishing a similar purpose.

Although the bathing accessory described 45 above is intended primarily as a shelter when changing clothes, it may also serve other purposes on the beach. It may be used as a spread on which the bather may recline, or, if desired, by getting into the accessory itself it may afford 50 protection from the direct rays of the sun, particularly if it is equipped with a hood or helmet 36, Fig. 8, attached to the edge 6. It may also serve as a storage place for clothes to keep out 55 the sand or water of the beach. By folding the accessory in the manner shown in Fig. 3, as previously noted, it may be used as a bag for transporting articles to and from the beach.

The bathing accessory can be made of almost 60 any fabric which is sufficiently opaque but preferably the material should be light in weight and waterproof.

It will be noted that no metal or other hard parts are used in the construction of the accessory; it is therefore entirely flexible and may, if desired, be readily folded for insertion in a suitable container.

I claim:

1. A bathing accessory comprising a tubular body open at the top and bottom, said top opening being of sufficient width to admit a human body and means for contracting the top opening. 10

2. A bathing accessory comprising a tubular body having openings at the top, bottom and sides, said top opening being of sufficient width to admit a human body and means for contracting the top opening. 15

3. A bathing accessory comprising a tubular body having openings at the top, bottom and sides, said sides of sufficient width to allow any article of clothing to be drawn in or out of accessory, means for contracting the top opening, 20 and means for contracting the side openings.

4. A bathing accessory comprising a tubular body having openings at the top, bottom and sides, said top opening being of sufficient width to admit a human body and expandable means 25 associated with each of the openings for independently maintaining them in normal contracted condition.

5. A bathing accessory comprising a tubular body, open at the top, said top opening being 30 of sufficient width to admit a human body and means for contracting the top opening.

6. A bathing accessory comprising a tubular body closed at the bottom and provided with 35 openings at the top and sides, said top opening being of sufficient width to admit a human body and means for contracting the top opening.

7. A bathing accessory comprising a tubular body closed at the bottom and provided with 40 openings at the top and sides, said sides of sufficient width to allow any article of clothing to be drawn in or out of accessory, means for contracting the top opening, and means for contracting the side openings.

8. A bathing accessory comprising a tubular 45 body closed at the bottom and provided with openings at the top and sides, said top opening being of sufficient width to admit a human body, expandable means for maintaining the openings in normal contracted condition, and means for 50 covering the side openings.

9. A bathing accessory comprising a tubular body closed at the bottom and provided with 55 openings at the top and sides, said top opening being of sufficient width to admit a human body, expandable means for maintaining the openings in normal contracted condition, and flaps attached to the front of the tubular body and above and below the side openings to cover the said side openings.

HARRY SHOGLOW.
